UNITED STATES PATENT OFFICE.

ALBERT M. STILES AND SAMUEL B. STILES, OF PARKERSBURG, WEST VIRGINIA.

DESIGN FOR A SHOE SCRAPER AND CLEANER.

No. 38,435.

Specification for Design.

Patented Jan. 29, 1907.

Application filed December 22, 1906. Serial No. 349,195. Term of patent 7 years.

To all whom it may concern:

Be it known that we, ALBERT M. STILES and SAMUEL B. STILES, citizens of the United States, residing at Parkersburg, in the county of Wood and State of West Virginia, have invented a certain new, original, and ornamental Design for Shoe Scrapers and Cleaners, the accompanying drawing illustrating the same in perspective.

We claim—

The ornamental design for a shoe scraper and cleaner, as herein shown.

ALBERT M. STILES.
SAMUEL B. STILES.
